NELSON C. HOLTJE, Primary Examiner

FIG. 1 is a right front isometric view of a plastic tape splice locating device, showing my new design;

FIG. 2 is a front elevational view thereof;

FIG. 3 is a top plan view thereof;

FIG. 4 is a right side elevational view thereof; the left side being substantially similar thereto with the lever omitted; and

FIG. 5 is a rear elevational view thereof.

I claim:

The ornamental design for a plastic tape splice locating device, as shown.
